UNITED STATES PATENT OFFICE.

LEO G. HAASE, OF PASADENA, CALIFORNIA.

DESIGN FOR A FLOWER-POT.

44,563.

Specification for Design.

Patented Aug. 26, 1913.

Application filed March 10, 1913. Serial No. 753,439. Term of patent 7 years.

To all whom it may concern:

Be it known that I, LEO G. HAASE, a citizen of the United States, residing at Pasadena, in the county of Los Angeles and State of California, have invented a new, original, and ornamental Design for Flower-Pots, of which the following is a specification, reference being had to the accompanying drawing, forming part thereof.

Figure 1 is a perspective view of my or-

namental flower pot. Fig. 2 is a plan view of the same.

I claim:

The ornamental design for a flower pot as shown.

LEO G. HAASE.
